WASHING IMPLEMENT

Max Thienel, Waiblingen, Wurttemberg,
GermanyApplication January 12, 1938, Serial No. 184,647
In Germany September 3, 1936

1 Claim. (Cl. 15—222)

My invention relates to a washing implement made of a suitable fabric which may serve for washing and rubbing the back and may be converted into a washing glove.

5 In the drawing affixed to this specification and forming part thereof an embodiment of my invention is illustrated diagrammatically by way of example in a perspective view.

Referring to the drawing, 1 is a strip of about 10 towel length of an absorbent fabric, for instance of the double loop kind, and 2 is another piece of the same or similar material, about the length of a hand, fixed to the strip 1. The piece of fabric 2 is wider than the strip 1 and folded at 3. 15 It is fixed to the strip 1 by sewing over about three quarters of its periphery, about one half of its length being left free on one side so as to form an aperture 4 through which the hand can be introduced into the pocket formed by the strip 1 and the piece of fabric 2.

If the strip 1 is gripped at either end, its middle part carrying the folded piece of fabric 2 can be pulled back and forth in contact with the back and can be used similarly as a bathing brush to 25 rub and wash the back. It can however also be used as a washing glove by inserting the hand through the aperture 4. In order to convert it into a particularly absorbent washing glove, the middle part carrying the piece of fabric 2 may be 30 turned inside out, whereby the left hand part of the strip 1 is enclosed between the two pieces and into the pocket then created the right hand part of the strip 1 can be inserted also, so that the pocket is filled with absorbent fabric which 35 is capable of holding a large quantity of water, room being left for introducing the hand and handling the device after the manner of a washing glove.

Obviously this implement, although being par-

ticularly efficient, is very simple in design and correspondingly inexpensive in manufacture. All hard parts and materials including leather, press buttons, etc., are avoided. The fold 3 enables the strip to be made rather narrow, while affording sufficient room for the hand introduced into the device. It is adapted as a substitute for sponges, bathing brushes, washing gloves and the like.

Instead of fixing the piece of fabric 2 on a comparatively long strip, the middle part of the strip 1 with the folded piece of fabric 2 fixed thereon may be fitted between two narrow ribbons 5.

I wish it to be understood that I do not desire to be limited to the exact details of construction 15 shown and described for obvious modifications will occur to a person skilled in the art.

I claim:

A bath appliance consisting of two elongated pieces of water absorbent material arranged in 20 superposition, one of said pieces comprising extensions projecting to both sides of the other, shorter piece, said pieces being connected with each other along one long side, the two narrow sides and part of the second long side of said 25 shorter piece whereby to leave an opening in the second long side and forming a pocket extending over substantially the entire area of the shorter piece, one of said pieces being substantially wider than the other one but formed with a longitudinal pleat normally reducing its effective width to that of the narrower piece, whereby the pocket formed intermediate said pieces when turned inside out with the extensions contained in the reversed pocket, will also allow the introduction 30 of a hand and will serve as a washing glove of high absorptive capacity.

MAX THIENEL.
